COLD CATHODE GLOW DISCHARGE COUNTING AND SCALING TUBES AND CIRCUIT ARRANGEMENTS THEREFOR

Christopher Haly Tosswill and George Frederick Weston, Reigate, and Terence Eugene Days, Crawley, England, assignors, by mesne assignments, to North American Philips Company, Inc., New York, N. Y., a corporation of Delaware

Application April 14, 1955, Serial No. 501,376

8 Claims. (Cl. 315—84.6)

This invention relates to devices, more particularly but not exclusively for use in counting circuit-arrangements, comprising at least one glow-discharge tube having an anode and in addition a number of main cathodes which determine the stable discharge portions or rest positions of the tube and are each associated with a number of auxiliary electrodes, and in which tube the discharge is transferred from one rest position to the next by negative pulses on the control electrodes. Furthermore, the invention concerns a glow discharge tube for use in such devices.

Tubes for use in such devices are known, in which the negative control pulses are delivered to auxiliary cathodes located between the main cathodes, the auxiliary cathodes having to fix the discharge for a while until the first main discharge path has been deionized. This requires control impulses of considerable energy which cannot be delivered by such a tube itself, so that cascade circuit-arrangements counting with two or more figures require the interposition of an amplifier; thus the device becomes more complicated and costly. The present invention has for its object to provide a device to which only pulses of such a value need be supplied as to permit the use of cascade circuit-arrangements without intermediate amplification. In circuit-arrangements comprising only one glow discharge tube it is also advantageous to use a pulse of low energy since in this case less pre-amplification is necessary.

According to the invention, a device particularly intended for use in counting circuit-arrangements comprises at least one glow discharge tube having an anode and a number of main cathodes, which determine the rest positions of the tube and each of which is associated with a number of auxiliary electrodes. In the glow discharge tube the discharge is transferred from one rest position to the next by negative pulses on the control electrodes. Auxiliary cathodes are provided near each main cathode in such manner that, during operation the auxiliary cathode associated with a main cathode assumes the potential of the main cathode, the main and auxiliary cathodes jointly constituting a rest group. A transfer group is located between every two such rest groups, and comprises in spatial order: a control electrode, an extinguishing electrode and a transfer electrode. The main cathodes are connected through resistors to a point of negative potential in the circuit arrangement, the anode is connected through a resistor to the point of maximum positive potential, the extinguishing electrodes are connected through a resistor to a potential which is more positive than those of the cathodes, and the interconnected auxiliary cathodes and transfer electrodes are connected to a potential in between that of the extinguishing electrodes and the anode, while all the electrodes, except the control electrodes and the anode, are connected through capacitors to a point of fixed potential, preferably ground.

2

With a sufficiently negative control pulse on the control electrodes, the control electrode nearest the cathode in operation withdraws a given current from the discharge, as a result of which the anode voltage tends to drop. Due to the discharge towards the control electrode the nearby extinguishing electrode is enabled to partake in the discharge in such manner that the discharge to the main cathode becomes extinguished and the discharge to the control electrode is also of short duration. 5 Due to transfer of the discharge the potential of the extinguishing electrode rises to such a degree that the nearest transfer cathode, the potential of which has meanwhile dropped, can take over the discharge. The main cathode of the next rest group is located adjacent 10 said transfer cathode and is at a very low potential so that it takes over the discharge. The associated auxiliary cathode, which is connected to the transfer electrode having operated last, then assumes the potential of the main cathode, the discharge remaining on this main cathode. 15 Due to the presence of the transfer cathodes, which have the potential of the auxiliary cathodes, the discharge travels only in one direction on applying a negative control pulse.

In order that the invention may be readily carried 25 into effect it will now be described with reference to the accompanying drawings, given by way of example, in which:

Fig. 1 is a perspective view of the electrode system for 30 a binary glow discharge tube in accordance with the invention;

Fig. 2 is a plan view of decade counter tube in accordance with the invention;

Fig. 3 is a schematic diagram of a circuit-arrangement 35 comprising a counter tube in accordance with the invention;

Fig. 4 is a graphical representation of the variation of the voltages on the several electrodes; and

Fig. 5 is a schematic diagram of a cascade circuit-arrangement of two counter tubes in accordance with the 40 invention.

In Fig. 1, an insulating disc 1 carries ten electrodes, that is two rest groups, comprising main cathodes 5, 10 and auxiliary cathodes 6, 11 respectively. The two transfer groups comprise control electrodes 7, 12, extinguishing electrodes 8, 13 and transfer electrodes 9, 15. 45 Only the cathodes 5, 10 are uncranked, whereas all the other electrodes have a cranked end pointed towards the preceding electrode or main cathode. A disc-shaped anode 2 is carried by a supply conductor 3. The electrode connections are not shown in the drawing. Input electrodes 7 and 12 are interconnected. The extinguishing electrodes 8 and 13 are interconnected, and furthermore the auxiliary cathodes 6, 11 and the transfer electrodes 9, 15 are connected together. Transfer of the discharge from one main cathode to the other occurs as 50 follows:

If a discharge is produced between the anode 2 and cathode 5, the electrode 6 assumes the potential of the cathode 5. Since the electrodes 9, 11 and 15 are interconnected they assume the same potential as that of the auxiliary cathode 6. In the case of a negative pulse being supplied to the control electrodes 7 and 12 the discharge will partially travel to electrode 7, thus striking the discharge to electrode 8 which is at a potential lower than those of the control electrodes 7 and 12, and the discharge to the cathode 5 extinguishes. Since, upon interruption of the discharge, the potential of the auxiliary cathode 6 drops, that of the transfer electrode 9 also drops so that it takes over the discharge from the extinguishing electrode 8 and transfers it to the main cathode 10 which is at a lower potential. Upon a next

negative pulse the discharge returns to the main cathode 5. In contradistinction to known counting circuit-arrangements, in which the control electrode has to maintain the discharge for a while, the control electrode of the present tube need only ignite the next electrode; hence a pulse of much lower energy suffices.

Fig. 2 is a plan view of the electrode system of a decade counter tube which fundamentally corresponds to the binary counter tube shown in Fig. 1. The anode 2 (not shown) is arranged above an insulating disc 105 which carries fifty electrodes in all. There are ten rest groups, each comprising a main cathode denoted 100, 110, 120 . . . 190, and an auxiliary cathode 101, 111, 121 . . . 191. There are also ten transfer groups each comprising a control electrode 102, 112, 122 . . . 192, an extinguishing electrode 103, 113, 123 . . . 193 and a transfer electrode 104, 114, 124 . . . 194. All the electrodes, except the ten main cathodes, have a cranked end as may be seen from the drawings.

In the circuit-arrangement shown in Fig. 3 all the even numbered main cathodes are interconnected, grounded through a capacitor C_4 and connected through a resistor R_4 to a potential of -50 v. required for transfer of the discharge from a transfer group to a rest group. All the odd numbered main cathodes H 1, 3, 5, 7 are interconnected and, similarly to the even-numbered cathodes, are connected to ground and to -50 v. through elements C_3 , R_3 . The main cathode numbered H9 is separately inserted in the circuit-arrangement through elements C_5 and R_5 . The anode A is connected through resistor R_1 to a voltage of 350 v. The interconnected control electrodes I are connected through a diode D1 to a potential of +50 v., the anode of said diode being connected to the control electrode. The negative input pulses are supplied through a capacitor C_1 , as indicated symbolically by an arrow and a block voltage. Similarly to the control electrodes, all the auxiliary cathodes G and transfer electrodes F, are connected through a diode D2, to a potential of +50 v. and are grounded through a resistor R_6 in parallel with a capacitor C_6 .

The extinguishing electrodes are grounded through a resistor R_2 shunted by a capacitor C_2 . During operation of the tube, the control electrodes and the auxiliary cathodes with the transfer electrodes may attain a positive potential not exceeding 50 v. due to the presence of the diodes D1 and D2. The resistors R_3 , R_4 and R_5 are so chosen that during the passage of the discharge to the main electrode, these electrodes, like the auxiliary electrodes, are at a potential of approximately 50 v. During the passage of the discharge to the main cathode H9 and the associated auxiliary cathode Go, a negative pulse on the control electrode Io produces a discharge to the extinguishing electrode Eo. The current flowing to the extinguishing electrode Eo reduces the anode potential so that the discharge to the electrodes H9 and Go is interrupted. The voltage of all the auxiliary cathodes G and the transfer electrodes F drops due to interruption of the discharge, and upon ignition of the discharge of the extinguishing electrodes their potentials rise. Thus, the discharge of the extinguishing electrode Eo is taken over by the transfer electrode Fo, the potential of which rises again, with the result that the potential difference between main electrode H1 and transfer electrode Fo rises so that the discharge is taken over by the main electrode H1. Further pulses may cause the discharge to pass to the main electrode H9 and if the output terminal is connected to this electrode, a negative pulse occurs at said output terminal when the discharge of main cathode H9 passes to main cathode H9, thus completing a cycle. The output pulse may be used for a general indication or for controlling a next tube.

Fig. 4 shows in a vertical voltage scale, which is different for the several curves, and a horizontal time scale, which is the same for all the curves, the variation

of the potential of the several electrodes of the tube as shown in Fig. 2. V_a represents the potential of the anode, V_i indicates the potential of the control electrodes, the idealized pulse being represented as a rectangular block voltage, V_H represents the potential of the main cathode, the left and right half holding for two succeeding cathodes that is to say cathodes 100 and 110 respectively shown in Fig. 2; V_F shows the voltage of the auxiliary cathodes and transfer electrodes and V_E indicates the potential of the extinguishing electrodes. Along the broken lines, which indicate given instants in the time scale, are plotted the number of electrodes, a rising arrow indicating the passage of the discharge to a given electrode and a downwardly directed arrow indicating the extinction of the discharge passing to the electrode concerned.

Fig. 5 shows two cascade-connected counter tubes I and II. The electrodes of these tubes are indexed I and II. The circuit-arrangement of the first tube corresponds to that of the tube shown in Fig. 3 but, for simplification, a number of switch elements have been omitted. Furthermore, the main cathode, indexed "O," is no longer connected to the other even numbered main cathode but separately inserted in the circuit through a capacitor C_7 and resistor R_7 . The main cathode H9 of the first tube is connected to the control electrodes I_{II} of the second tube through a capacitor C_{11} . A positive voltage of 50 v. is applied to said control electrodes through a rectifier D_3 . The main cathode H_0 of the first tube is connected through a resistor R_8 to the extinguishing electrodes E_{II} of the second group. Moreover, said extinguishing electrodes are capacitatively grounded through a capacitor C_8 and grounded by way of a rectifier D_4 so that the voltage of said electrodes never becomes negative relative to ground. The even numbered main cathodes of the second tube are inserted in the circuit-arrangement with a capacitor C_{12} and resistor R_{12} , and the odd numbered cathodes with a capacitor C_{13} and resistor R_{13} . The anode A_{II} is connected through a resistor R_{10} to the positive terminal of the source of potential. If, in the first tube, the discharge travels to the main cathode H9, the capacitors C_{11} and C_5 are charged, and if the discharge thence passes to the cathode H_0 the discharge of said capacitors causes a negative pulse at the control electrode I_{II} . In order to ensure satisfactory operation of the circuit-arrangement, provision is made that the control electrodes I_{II} carry current prior to the capacitors C_5 and C_{11} becoming completely discharged. This may result in the passage of the discharge from the first tube H9 to H_0 acting as a double pulse on the control electrodes I_{II} with the result that the discharge would advance two steps in the second tube. This could be prevented by making the time constant of the switch elements at the interconnected auxiliary and transfer cathodes of the second tube, and also that of the main cathodes, high so that the discharge on an extinguishing electrode is maintained until the capacitors C_5 and C_{11} have become discharged. This, however, might lead to considerable time constants. Instead thereof, use is made of the said circuit-arrangement between the main cathode H_0 of the first tube and the extinguishing electrodes of the second tube, with the result that the extinguishing electrodes receive a positive pulse after the negative pulse on the control electrodes. The rectifier D_4 prevents the extinguishing electrodes of the second tube being driven negative relatively to ground. The time constant of the circuit R_8 and C_8 is chosen high, that is to say approximately five times as high as that of the circuit C_7 and R_7 , so that the control electrodes, under the influence of a possible double pulse, yet control the discharge only once.

If, in Figs. 3 and 5, in lieu of the circuit-arrangement shown in Fig. 3, a different circuit-arrangement is used for the control electrodes of the first tube; that is, an arrangement in which the control electrodes are at a considerable negative potential through a high resistor

so that an auxiliary current of a few microamperes flows to the control electrode, the sensitivity to small pulses may be higher, but then the attainable switching rate is lower.

What is claimed is:

1. A circuit arrangement comprising a glow discharge tube having an anode, a plurality of electrode groups each comprising a main cathode, an auxiliary cathode, a control electrode, an extinguishing electrode and a transfer electrode, said auxiliary cathode defining with said main cathode a rest group and being positioned in operative relation to said main cathode in such a manner that it assumes the potential of said main cathode when said main cathode carries the discharge of said tube, said control electrodes, extinguishing electrodes and transfer electrodes constituting a plurality of transfer electrode groups interposed between adjacent ones of said rest groups for transferring the said discharge from one of said rest groups to another upon the application of a negative pulse to said control electrode, means for interconnecting said transfer electrodes and said auxiliary cathodes, means for applying an input signal to said control electrodes, a first voltage source having a negative polarity terminal and a positive polarity terminal, resistance means for connecting each of said main cathodes to said negative terminal, a second voltage source of substantially greater magnitude than that of said first voltage source having a positive polarity terminal, resistance means for connecting said anode to the positive terminal of said second voltage source, resistance means for connecting said extinguishing electrodes to a point at ground potential, means for connecting said auxiliary cathodes and said transfer electrodes to the positive terminal of said first voltage source, capacitance means for connecting said main cathodes, said extinguishing electrodes, said auxiliary cathodes and said transfer electrodes to a point at ground potential, and means for deriving an output signal from one of said main cathodes.

2. A circuit arrangement as claimed in claim 1, further comprising rectifier means for connecting said control electrodes to the positive terminal of said first voltage source, said means for applying an input signal to said control electrodes including a capacitor connected to said control electrodes.

3. A circuit arrangement as claimed in claim 1, further comprising resistance means having a relatively high resistance value for connecting said control electrodes to a point at negative potential.

4. A circuit arrangement as claimed in claim 1, further comprising resistance means for connecting said auxiliary cathodes and said transfer electrodes to a point at ground potential and rectifier means for connecting said control electrodes to the positive terminal of said first voltage source, said means for connecting said auxiliary cathodes and said transfer electrodes to the positive terminal of said first voltage source comprising a rectifier having an anode connected to each of said auxiliary cathodes and said transfer electrodes and a cathode connected to the positive terminal of said first voltage source.

5. A glow discharge tube having an anode, a plurality of electrode groups each comprising a main cathode, an auxiliary cathode, a control electrode, an extinguishing electrode and a transfer electrode, said auxiliary cathode defining with said main cathode a rest group and being positioned in operative relation to said main cathode in such a manner that it assumes the potential of said main cathode when said main cathode carries the discharge of said tube, said control electrodes, extinguishing electrodes and transfer electrodes constituting a plurality of transfer electrode groups interposed between adjacent ones of said rest groups for transferring the said discharge from one of said rest groups to another upon the application of a negative pulse to said control electrode, and means for interconnecting said transfer electrodes and said auxiliary cathodes.

6. A glow discharge tube as claimed in claim 5, further comprising a support member comprising electrically insulating material, said main cathodes comprising rods transversely supported in said support member, said auxiliary cathodes, said control electrodes, said extinguishing electrodes and said transfer electrodes each comprising a rod having a main stem transversely supported in said support member and a minor stem appended to an end of said main stem and angularly disposed from said main stem, said last-mentioned rods being so positioned that their minor stems are in predetermined angular relation with each other, the ends of said main cathode rods and the minor stems of said last-mentioned rods being positioned substantially equidistantly from the surface of said support member.

7. A circuit arrangement comprising a pair of glow discharge tubes each having an anode, a plurality of electrode groups each comprising a main cathode, an auxiliary cathode, a control electrode, an extinguishing electrode and a transfer electrode, said auxiliary cathode defining with said main cathode a rest group and being positioned in operative relation to said main cathode in such a manner that it assumes the potential of said main cathode when said main cathode carries the discharge of said tube, said control electrodes, extinguishing electrodes and transfer electrodes constituting a plurality of transfer electrode groups interposed between adjacent ones of said rest groups for transferring the said discharge from one of said rest groups to another upon the application of a negative pulse to said control electrode, means for interconnecting said transfer electrodes and said auxiliary cathodes, means for applying an input signal to the control electrodes of the first of said tubes, a first voltage source having a negative polarity terminal and a positive polarity terminal, resistance means for connecting each of the main cathodes of said tubes to said negative terminal, a second voltage source of substantially greater magnitude than that of said first voltage source having a positive polarity terminal, resistance means for connecting the anode of each of said tubes to the positive terminal of said second voltage source, resistance means for connecting the extinguishing electrodes of said tubes to a point at ground potential, means for connecting the auxiliary cathodes and the transfer electrodes of said tubes to the positive terminal of said first voltage source, capacitance means for connecting said main cathodes, said extinguishing electrodes, said auxiliary cathodes and said transfer electrodes to a point at ground potential, means for coupling one of the main cathodes of the first of said tubes to the control electrodes of the second of said tubes, means for coupling another of the main cathodes of the first of said tubes to the extinguishing electrodes of the second of said tubes comprising a circuit having a relatively long time constant, and means for deriving an output signal from one of the main cathodes of the second of said tubes.

8. A circuit arrangement as claimed in claim 7, wherein in said means for coupling one of the main cathodes of the first of said tubes to the control electrodes of the second of said tubes comprises a capacitor and said means for coupling another of the main cathodes of the first of said tubes to the extinguishing electrodes of the second of said tubes comprises a resistor connected between the said other of said main cathodes and each of the extinguishing electrodes of the second of said tubes, a capacitor and a rectifier connected in parallel circuit arrangement with said capacitor, said parallel circuit arrangement being connected in series with said resistor, said resistor and said capacitor having a relatively long time constant and said rectifier being connected with a polarity which prevents the extinguishing electrodes of the second of said tubes from being driven negative relative to said point at ground potential, and further comprising

rectifier means for connecting the control electrodes of the second of said tubes to the positive terminal of said first voltage source.
